UNITED STATES PATENT OFFICE.

FIRM B. BYERS, OF NEW YORK, N. Y.

DESIGN FOR A COLLAR CLASP.

60,123.

Specification for Design.

Patented Jan. 3, 1922.

Application filed May 3, 1921. Serial No. 466,621. Term of patent 3½ years.

To all whom it may concern:

Be it known that I, FIRM B. BYERS, a citizen of the United States, residing in New York, in the county of New York and State of New York, have invented a new, original, and ornamental Design for Collar Clasps, of which the following is the specification, reference being had to the accompanying drawing, forming part thereof.

The figure is a perspective view of a collar clasp, showing my new design.

I claim:

The ornamental design for a collar clasp, as shown.
